UNITED STATES PATENT OFFICE.

MAURIZIO BARRICELLI, OF ROME, ITALY.

PROCESS FOR MAKING ARCHETYPES.

No. 909,980

Specification of Letters Patent.

Patented Jan. 19, 1909.

Application filed June 2, 1904. Serial No. 210,769.

To all whom it may concern:

Be it known that I, MAURIZIO BARRICELLI, a subject of the King of Italy, residing at Rome, Italy, have invented a new and useful Improvement in Processes for Making Archetypes; and I do hereby declare the following to be a full, clear, and exact description of the same.

As is well known, photographic negatives have been used hitherto only for the positive reproduction on sensitized paper, or for the production of cliches or stereo-types or other similar preparations sensitive to light.

The object of the present invention is to transform the negatives into archetypes by which the positives can be printed with the same results as with collography; the photographic negatives become stereotype plates, and can be substituted also for the ordinary photographic cliches.

The well known action which chrome salts exercise on gelatin is generally utilized in graphic arts, and specially in collotypy and photoreliiefs. It is further known that gelatins treated with a solution of chrome salts and exposed afterwards to the action of light, lose their solubility, extensibility, and permeability and become capable of receiving printing ink.

By exposing a plate of gelatin or chromated albumen to the light after placing the same under a photographic negative, each part of the gelatin or albumen which receives the action of the light that passes through the corresponding parts of the negative, will require more or less the aforesaid properties according to the greater or less transparency of the superposed negative. By immersing afterwards the gelatin plate in water, the gelatin will swell up more or less on the different parts according to the intensity of the action of the light on those parts of the gelatin. We thus obtain a positive picture in relief, which can be used for several photo-

mechanical operations and for impressions for printing ink. This process requires naturally an auxiliary plate as the negative serves only as a screen to determine the intensity of the action of the light on each particular part of the plate and for this reason the negative itself could not be subjected to the aforesaid treatment. In the process of photo-archetypy as hereinafter described, chrome salts are used in order to produce the positive relief picture, direct on the negative itself, avoiding thus all other secondary

operations such as the reversing of the picture, reproduction of other positives and the like. The great advantages which this new process of photo-archetypy presents over the ordinary process with the chrome-gelatin are quite evident.

Referring to the accompanying drawings, Figure 1. is a cross-sectional view, showing the sensitive layer between the glass plate and a metallic plate; Fig. II is a diagrammatic view, showing the refraction of light from a polished glass plate, and Fig. III is a diagrammatic view, showing the refraction of light from a polished metallic plate; Fig. IV is a cross-sectional view, showing the application of the invention with a layer of two parts, one of which is not acted upon by the light.

The method of working this process is as follows: After having obtained a bromid silver gelatin photographic negative and having developed it by preference in a solution of amidol and sulfite of soda, (other developers not excluded), and having fixed the same in a bath of hyposulfite of soda, and then dried in a dark place, the dried negative is then immersed in a solution of bichromate of potassium or bichromate of ammonium and alcohol in suitable proportions according to the nature of the negative. Afterwards the negative is again dried in a dark place and is then placed on a specular surface such as a silvered plate, or other polished metal plate, or a layer of mercury, or any other reflecting surface is then applied on the negative film. The negative is placed on the reflecting metallic surface in such a manner (see Fig. I) that the layer 4 of sensitive substance shall be comprised between the polished reflecting metallic surface 3 of a metallic plate 1 and the surface 6 of the glass plate 5 to which the sensitive layer is adherent.

The film placed on the reflecting surface is now exposed to the action of actinic light with the side of the glass plate turned towards the natural or artificial light for the necessary period which depends on the intensity of the light.

The use of a metallic mirror, instead of a glass one, gives a better utilization of the action of light, as will be easily understood. Referring to Figs. II and III, if we consider a thick glass plate, one of the polished surfaces (for example, 10) is spread with a layer of amalgam, silver or any other

substance, we note that an incident ray 13 of light undergoes two refractions in passing from the air to the glass and from the glass to the air, after a reflection on surface 10, instead of a simple reflection (as shown in Fig. III) on the polished surface of a metallic mirror 14. Now, having regard to Fig. IV (which represents a section of a metallic plate 16 with the negative supplied thereunto—with the proportions of the parts not preserved, as this facilitates explanations) let it be assumed that the layer, 17, of sensitive substance corresponds to a part not acted upon by the light and that the part 17¹, shown by hatched lines corresponds to a part acted upon by the light. As will be seen, the fresh layer of sensitive material applied to the negative film will be rendered more or less insoluble, according to the greater or less intensity of the rays of the light passing through the negative film. Towards the part H, where the darkened layer is of very great thickness a ray of light, normal to the surface, 19, of the glass plate, 18, will, while passing through the negative 21 on said plate lose a large part of its intensity in reaching the surface 20, and the degree of insolubility produced in the fresh sensitive layer will be smallest; towards H, the ray of light will keep almost the whole of its intensity and the highest degree of insolubility will be obtained. In any case, the ray of light normal to the mirror will be reflected in its own direction, so that the field of light, whose action produces insolubility, is not only increased but automatically regulated, for the action of each reflected ray is in inverse proportion to the loss of luminous intensity, that is to say, in proportion to the work it has to perform.

After exposure as aforesaid, the negative is thoroughly cleansed in fresh water and after it has been completely dried, is ready for the photo-archetype. This photo-archetype (meaning thereby a stamp which can directly be used for printing, and from which pictures can be obtained by an ordinary impression as from a "cliche") may be used for producing impressions, with 50 printing ink on paper, cloth or any other even surface. The positive picture might also be detached from the glass plate and applied to a surface of celluloid or on a metal plate for ordinary typographic uses. 55 This positive relief picture can also be used for the reproduction of printing blocks for galvano-plastics or typographic cliches.

This new photo-archetype may also be applied to the three color photography, by 60 transforming the three monochromatic negatives in three photo-archetypes by which the positive picture is to be impressed with the three respective colored printing inks, and without the aid of the usual nets. 65

I claim:

A process for producing a photographic negative transformable into an archetype suitable for use in printing, consisting in sensitizing and applying a fixed and dried 70 bromid silver gelatin photographic negative to a metallic reflecting surface, exposing the same to active light for a convenient space of time, and finally washing and drying the same.

In testimony whereof I have signed this specification in the presence of two subscribing witnesses.

MAURIZIO BARRICELLI.
